ABSTRACT OF THE DISCLOSURE

A ladder assembly for arrangement on the side of a structure to provide access onto the structure has a support member and means for securing it to the structure. A plurality of steps arranged at intervals along the support member each include a pair of angularly related, elongated plates presenting a pair of upwardly facing, spaced apart angular edges as a stepping surface.

The present invention relates to a novel ladder assembly to provide access onto a structure. The ladder assembly is particularly adaptable for use on large vehicles such as earthmoving machinery. Ladder assemblies in the prior art for use on structures of the type contemplated by the present invention normally have steps formed with either round or flat bearing surfaces which tend to become slippery when wet or muddy. Even though the steps are commonly formed with antiskid surfaces, they tend to retain mud or other matter so that personnel employing the ladders may encounter unsafe footing.

It is accordingly an object of the present invention to provide a ladder assembly having stepping surfaces which continually provide firm footing regardless of weather conditions.

Other objects and advantages of the invention are made apparent in the following description having reference to the accompanying drawing.

In the drawing:

FIG. 1 is a view in elevation of the ladder assembly as it would appear in place on the side of a structure,

FIG. 2 is a side view of the ladder assembly of FIG. 1;

FIG. 3 is a cross-sectional view of one of the steps in the ladder; and

FIG. 4 is a view taken along section line IV—IV of FIG. 1.

Referring now to the drawing, the ladder assembly of the present invention includes a plurality of steps 11 secured at suitable intervals to a structural support member 12 shown in cross-section by FIG. 4. The support member 12 has a pair of struts 13 and 14 for securing the support member 12 to the side of a vehicle or other structure. The struts 13 and 14 include mounting brackets 16 and 17. The struts 13 and 14 are preferably of unequal lengths so that the support member 12 may be mounted at an incline from a vertical plane and support the steps 11 along the same incline.

Each of the steps 11 includes a pair of elongated plates 18 and 19 which are cantilevered in spaced apart relation at intervals along the support member 12. The plates 18 and 19 extend upwardly in angular relation to have a stepping surface formed by angular edges 21 and 22 of

2

the plates 18 and 19 respectively. The plates 18 and 19 are preferably angled along their lengths, as best seen in FIG. 3, so that the lower portions of the plates 18 and 19 are spaced further apart than their upper edges 21 and 22. In this manner, the edges 21 and 22 tend to continually provide a good bearing surface for personnel using the ladder. The absence of level surfaces on the steps 11 tends to prevent the retention of water, mud, rock or other material which might otherwise deleteriously affect the footing provided by the steps. The angular relation of the plates 18 and 19 prevents mud or other material from being wedged within the central opening of each of the steps.

A guard member 23 is secured to the free end of the cantilevered plates 18 and 19 of the step and extends above the edges 21 and 22 to prevent an operator's foot from slipping off the end of the steps. The guard members 23 are preferably formed from arched rods so that the opening between the plates 18 and 19 is maintained along the cantilevered length of each of the steps.

The present invention accordingly provides a ladder assembly including steps having an improved nonslip bearing surface formed by the angular edges 21 and 22 of the plates 18 and 19. As an operator mounts the steps, the edges tend to grip his shoe sole and prevent slippage. As noted above, the absence of flat surfaces tends to prevent the retention of water, mud or rocks while the configuration of the plates 18 and 19 tends to permit self cleaning of the steps and provide improved footing in all kinds of weather.

What is claimed is:

1. A ladder assembly for disposition on the side of a structure to provide means for mounting and dismounting from the structure, comprising a support member and means for securing it in a generally vertical plane and a plurality of steps arranged at intervals along the support member, each step including a pair of spaced apart, elongated plates extending angularly upwardly toward each other along the length of the step and presenting a pair of upwardly facing, spaced apart angular edges as a stepping surface.

2. The invention of claim 1 wherein the plates forming each step are cantilevered from the support member with a guard member joining the free ends of the plates and extending upwardly from the stepping surface formed by the plates.

3. The invention of claim 2 wherein each of the step plates is angularly formed along its length and the guard members are arched rods to maintain a spaced opening for each step along its cantilevered length.
